SUPERHEATER.

Application filed December 7, 1923. Serial No. 679,159.

This invention relates to improvements in superheaters.

The primary object of this invention is the provision of a superheater unit of the type adapted for use in the flue tubes of boilers or the like, so that the heated gases from the boiler may be used for heating saturated steam which flows into the superheater unit for the purpose of drying and 10 superheating the same.

A further object of this invention is the provision of a novel type of superheater embodying a construction which will permit of the facile assemblage of the unit in a 15 flue or other member of like character, and so that the heated gases may always be insured of a free flow about the superheater for heating a maximum surface thereof.

A further object of this invention is the 20 provision of a superheater unit of the above mentioned character embodying a system for the conduction of saturated steam there-through for superheating purposes, operating in an efficient manner to perform the 25 purpose for which it is adapted.

A further object of this invention is the provision of a superheater unit for heating flues and the like of steam locomotive or stationary boilers designed so that the same is 30 accessible at all times for cleaning purposes, and preferably being of a character to render the same interchangeable with the Schmidt type of superheater, although operating on an improved principle overcom- 35 ing many defects which are well known with this type of superheater.

Other objects and advantages of this invention will be apparent during the course of the following detailed description.

In the accompanying drawings, forming a 40 part of this specification, and wherein similar reference characters designate corresponding parts throughout the several views.

Figure 1 is a longitudinal cross sectional view taken through the preferred type of 45 superheater unit, showing the same in its assembled relation within the flue of a boiler or the like.

Fig. 2 is a cross sectional view taken sub- 50 stantially on the line 2-2 of Figure 1.

Fig. 3 is a longitudinal cross sectional view taken through the improved superheater unit substantially on the line 3-3 of Figure 4.

55 Fig. 4 is an end elevation, partly in cross

section, of the improved superheater unit.

Fig. 5 is a longitudinal cross sectional view through a modified form of superheater unit embodying the essential principles of the unit illustrated in Figures 1 to 4 inclusive, although constructed after a different method than the same.

Fig. 6 is a cross sectional view taken substantially on the line 6-6 of Figure 5.

Fig. 7 is a cross sectional view taken 65 through the improved superheater unit substantially on the line 7-7 of Figure 5.

Fig. 8 is a front elevation, partly in section, of the improved superheater unit illustrated in Figure 5.

Fig. 9 is a longitudinal cross sectional view taken through the improved superheater unit substantially on the line 9-9 of Figure 8.

Fig. 10 is a longitudinal cross sectional 75 view taken through a further form of superheater.

Fig. 11 is a plan view of the superheater shown in Figure 10.

Fig. 12 is an end view of the superheater 80 shown in Figure 11.

Figs. 13 and 14 are cross sectional views taken on their respective lines in Figure 11 of the drawings.

In the drawings, wherein for the purpose 85 of illustration are shown the forms of the improved superheater unit and the manner in which they are used in connection with a heating flue or tube, the letter A may generally designate the heating flue or tube, 90 which may be a part of a boiler, and within which the improved types of superheater units B, C or D may be used.

Referring to the heater flue construction A, the same is preferably supported at its 95 front end in the front wall 10 of a boiler, having the outwardly extending flange 11 which overlies the front surface of the plate 10. The flue A for the major length of the body portion 12 thereof is of uniform 100 diameter, providing a passageway 13^a therethrough. At a distance from the plate 10 the tube A converges in diminishing relation, as at 13, to restrict the passageway 105 through the flue A.

Referring to the superheater unit B, the same preferably comprises an inner substantially cylindrical shaped member 20, which is of the uniform diameter from end to end, and provides a passageway 21 therethrough. 110

On diametrically opposed sides of the cylindrical shaped casing or member 20 flanges 22 and 23 are welded, or otherwise secured thereto; these flanges 22 and 23 being in 5 the nature of partition walls, as will be subsequently described, and extending for the major length of the tube 20, from its front edge, although not extending the full length thereof. An outer substantially cylindrical 10 shaped member or casing 25 is provided, which is provided with longitudinal slots 26 and 27 extending for the major length thereof from the front edge. At its rear end the member 25 tapers with a gradually 15 diminishing diameter, as at 28; the slots 26 and 27 terminating short of this tapered portion 28.

The tubular member 20 is connected in 20 concentric relation within the tubular member 25; the member 20 at its front end being welded, as at 29, to the forward end of the tapered portion 28. The partition walls or flanges 22 and 23 extend respectively in the slots 26 and 27 of the member 25 and 25 are suitably welded therein, substantially as is illustrated in the drawings, so that they entirely fill said slots. A front wall 31, of substantially ring shaped formation is welded to the rear edges of the cylindrical 30 shaped inner and outer members 20 and 25 respectively, to enclose the compartment defined by the space between the inner and outer members 20 and 25. This compartment or space between the tubular members 35 20 and 25 is sub-divided by the partition walls 22 and 23 into compartments 35 and 36 which are in relative communication at the rear end of the unit B, through the passageways 37. The passageways 37 are formed 40 by reason of the termination of the partition walls 22 and 23 short of the tapered portion 28 of the tubular member 25. At the front end of the unit B interiorly screw threaded extensions 39 and 40 are integrally provided 45 with the cylindrical shaped portion 25, which respectively provide inlet and outlet openings 41 and 42 for the compartments 35 and 36.

Referring to the assemblage of the unit B 50 within the flue A, supporting legs 45, of substantially I-shaped formation are radially positioned in the passageway 13^a of the flue A, and are welded to the portion 25 of the superheater unit B, to support the superheater unit B in an eccentric relation within the passageway 13^a of the heater flue A. While the axes of the superheater unit B and the flue A are parallel, yet the supporting legs 45 maintain the superheater unit B in 55 such relation within the passageway 13^a that the lower portion of the superheater unit is spaced a greater distance from the lower part of the passageway 13^a than the upper portion of said unit is spaced with respect to 60 the top of the flue A, and substantially as

is illustrated in Figure 2 of the drawings. This arrangement of the superheater unit B in the flue A permits of some settlement of soot and foreign material in the lower portion of the passageway 13^a, without impeding the draft or the effective playing of 70 heated gases over the entire exposure of the superheater unit B. The legs 45 are also so positioned that the tapered end 28 of the unit B is disposed in proximity to the tapered 75 portion 13 of the flue A, for the efficient guiding of exhaust gases over the exposed surfaces of the superheater unit B. At its front end the superheater unit B extends sufficiently out of the flue passageway 13^a, 80 that the inlet and outlet openings 41 and 42 may suitably receive therein parts of couplings by means of which saturated steam may be led into the superheater and the superheated steam led therefrom. 85

Referring to the operation of this invention the saturated or wet steam enters the superheater compartment 35 through the inlet opening 41, and passes longitudinally of this compartment 35 toward the rear end of 90 the superheater unit B. Thus, the saturated steam travels against the flow of the exhaust gases, which as is well understood are heated, and flow in the space between the outer casing portion 25 of the superheater unit 95 B, and the walls of the flue A. The saturated steam is dried as it advances toward the rear of the unit B, and through the passageway 37 enters the compartment 36 and is directed from the rear toward the front 100 of the compartment B and exits through the opening 42 of the unit B in a superheated condition. The heated gases which flow through the flue A, of course, are given an easy pitch by reason of the tapered portion 105 28 of the unit B, which enters the tapered portion 13 of said flue A; the heated gases flowing in the flue A, of course, passing through the passageway 21 of the inner casing 20 of the unit B, as well as passing 110 around and in the space between unit B and the flue A.

Referring to the construction of the superheater unit C, the same is connected in the flue A in the same manner as the unit B 115 above described, and this unit also embodies the fundamental features of the unit B. It preferably comprises an inner casing construction 50, which is formed of two elongated sections 51 and 52, each comprising a 120 semi-circular portion 53 with the diametrically opposed and outstanding flanges 54 at the longitudinal edges thereof. These flanges 54 extend from the extreme front edge of the sections 51 and 52, but terminate 125 short of the opposite ends of said sections. An outer casing 55 is preferably provided, having the longitudinally extending slots 56 and 57 in diametrically opposed relation 130 therein, which extend from the front edge

of the casing or cylindrical portion 55, although they terminate short of the opposite end of said casing 55. The casing or member 55 at its rear end tapers in diminishing diameter, to provide a portion 59 substantially identical with the portion 28 of the unit B above described.

The inner casing construction 50 is, of course, assembled within the outer casing construction 55, and to this end the flanges 54 of the sections 51 and 52 are placed in abutting relation and are welded in the slots 56 and 57 of the outer casing or member 55, to entirely seal said slots, and to subdivide the interior of the outer casing 55 between the inner casing and the same into compartments 60 and 61, which have communication at the rear end of the unit C through the passageways 63; these passageways 63 intercommunicating said compartment, by reason of the fact that the flanges 54 do not extend for the entire length of the casing 55, and therefore do not partition said compartments from each other. A front wall 65 of substantially ring shaped formation is welded to the front edges of the casing portions or members 50 and 55, to seal the compartments at the front end of the unit C, and at its rear end the tapered portion 59 is welded to the rear end of the casing sections 51 and 52. The compartments 60 and 61 at the forward end of the unit C are respectively provided with the inlet and outlet openings 66 and 67, which are formed through suitable upwardly extending tubular extensions 69 and 70 respectively, substantially as provided for the unit B above described.

The unit C is assembled within the flue A exactly as described for the preferred embodiment of this invention, and the operation of the steam therethrough for the purpose of superheating is identically as above described for the superheater unit B.

Referring to the form of superheater D, the same is probably the most economical and practical form of superheater. The superheater comprises the elongated hollow sections 80 and 81, which are of identical formation and preferably substantially crescent shaped in cross section and respectively providing the longitudinally extending compartments 83 and 84 therealong which in cross section are also crescent shaped. These sections 80 and 81 are pressed into their crescent shape from tubular stock material, and at their flue inserting ends are each provided with elongated openings 85 and 86 in the upper and lower longitudinal edges thereof. The sections 80 and 81 at their flue inserting ends are drawn into a leak proof joint, with a tapered end 88 which lies within the area defined by the tapered portion 13 of the flue A when the superheater is in place. The sections 80

and 81 are placed together with their concave sides facing each other, and are welded at points 90 along their upper and lower marginal edges, to securely connect said sections 80 and 81 into a superheater which is circular in cross section and which provides the longitudinally extending gas passageway 92 therethrough open at both ends of the superheater. The longitudinal facing marginal edges of the sections 80 and 81 may be spaced to provide the longitudinal cracks or spacing 93 through which the heated gases in the flue may pass from the flue passageway 13^a into the superheater passageway 92, or vice versa, and thus providing an increased heating surface on the superheater unit D. Of course, the slots or openings 85 on the upper edges of the sections 80 and 81 are placed in abutting communicating relation, as are also the slots 86 in the lower edges of said sections. The sections 80 and 81 are then welded at 90^a about the slots or openings 85 and 86 in a steam tight weld, so that the compartments 83 and 84 upwardly communicate with each other through the aligning passageways 85, and below the compartments communicate with each other through the aligning passageways 86. At the outer ends of the sections 80 and 81, closure caps 95 may be welded or otherwise secured thereon to seal the compartments 83 and 84. Inlet and outlet extensions 97 and 98 are provided on the sections 80 and 81 respectively, which respectively provide inlet and outlet openings 99 and 100 for the superheater unit D.

The superheater unit D has the diagonal supporting legs 101 welded thereon in the manner above described for the other forms of this invention, so that when the superheater unit D is placed in the flue A it will be eccentrically disposed therein to provide a greater area of the passageway 13^a below said superheater unit D than is provided between the top of said superheater and the top of the flue A, and for a purpose which has been subsequently described. The steam is of course guided into the inlet opening 99 and from thence flows longitudinally through the compartment 83 toward the inner passageway of the flue A and the wet steam is gradually dried during such passage. The steam then passes from the compartment 83 into the compartment 84 through the passageways 85 and 86, and the steam is superheated during its passage in the compartment 84 toward the outlet opening 100. This form of invention provides a very durable and economical superheater which does away with much of the welding necessary for the other forms of invention.

From the foregoing description of this invention it is apparent that a superheater has been provided which may be conven-

iently attached in an ordinary flue of a boiler, so that the heated gases flowing therein may be taken advantage of for the purpose of superheating saturated steam.

- 5 The device is accessible so that soot, dirt, and other foreign materials may be readily reached and cleaned therefrom, and the fact that soot does settle in the flues of the pipe is well recognized, and the construction of
10 this invention has taken care of this feature so that the settlement of soot or foreign materials in the flue will not in any way obstruct the flow of the heated gases about the superheater for the purpose of heating the
15 maximum surface thereof. Therefore, the degree of heating of the steam within the superheater can be accurately determined and relied upon. The device is inexpensive and the maintenance expense in connection
20 therewith is negligible in contradistinction to the maintenance expense of ordinary superheaters which are inaccessible in the majority of instances.

Various changes in the shape, size, and
25 arrangement of parts may be made to the form of the invention herein shown and described, without departing from the spirit of this invention or the scope of the claims.

We claim:

- 30 1. As an article of manufacture a superheater unit comprising an inner cylindrical shaped casing, an outer cylindrical shaped casing having slots at diametrically opposed points thereon extending from one end
35 toward the other end for the major length thereof, partition walls welded to said inner casing on the outer circumference thereof and welded in the slots of said outer casing, and means sealing the inner and
40 outer casings at the ends thereof, said outer casing having inlet and outlet openings communicating with the space between the inner and outer casings.

2. In a superheater the combination of an
45 inner tubular casing straight throughout the length, an outer tubular casing of greater

diameter than the inner casing, means connecting said casings in a sealed relation at their ends, the outer casing at one end being tapered over a considerable length from intermediate its ends in converging relation to a sealed connection with the end of inner casing, said inner casing having a straight passageway therethrough of substantially uniform diameter from end to end, partition means in the space between the casings subdividing said space into compartments having communication with each other directly in the tapered end of the outer casing, and inlet and outlet port means for said compartments.

3. In a superheater construction the combination with a heating flue, of a single cylindrical shaped superheater unit in said heating flue eccentrically supported therein and including outer and inner tubular casings in spaced relation to provide a steam compartment, the tubular casings being sealed at opposite ends and the inner casing having a passageway longitudinally therethrough open in longitudinally aligning relation with the flue for passage of heated gases therethrough, the outer tubular casing being tapered in a converging relation at one end to constrict the steam compartment between said casings, the said tapered end facing countercurrent to heated gas travel through the flue, and partition means in the space between said casings subdividing the same into compartments which have inter-communication at the tapered end of the outer casing of said superheater unit, the flue having a passageway constricting portion therein into which the tapered outer casing end of the superheater directly extends to cause deflection of the heated gases externally of the superheater unit and through the passageway of the inner casing.
